UNITED STATES PATENT OFFICE.

EUGENE H. BALLOU, OF PAWTUCKET, RHODE ISLAND, ASSIGNOR TO DRAPER CORPORATION, OF HOPEDALE, MASSACHUSETTS, A CORPORATION OF MAINE.

SPENT-WEFT CUTTER.

1,272,600.

Specification of Letters Patent. Patented July 16, 1918.

Application filed August 6, 1917. Serial No. 184,703.

To all whom it may concern:

Be it known that I, EUGENE H. BALLOU, of Pawtucket, in the county of Providence and State of Rhode Island, have invented 5 a new and Improved Spent-Weft Cutter, of which the following is a specification.

In Letters Patent of the United States No. 1,244,827, October 30, 1917, there is set forth 10 an automatic weft replenishing loom wherein in the shuttle box at the replenishing side of the loom is brought to a standstill before the lay reaches its extreme forward position so that the shuttle is standing still during 15 the time that a fresh weft carrier is being inserted therein, this dwell of the shuttle and shuttle box being effected without interrupting the regular movements of the lay itself. The present invention consists in a spent weft cutter which is particularly adapted 20 for use in the loom described in the said patent. The improved spent weft cutter is mounted on the lay and the organization is such that when the shuttle box is stopped and the lay continues its forward movement 25 the spent weft cutter is actuated so as to cut the weft extending from the neighboring edge of the warp to the shuttle in the now stationary shuttle box. Coöperating with the spent weft cutter is a spent weft 30 clamp which clamps the strand of weft close to the cutter thus rendering certain the cutting action.

The invention is illustrated in the accompanying drawings, wherein—

Figure 1, is a plan view partly in section of so much of the lay and shuttle box as is necessary for an understanding of the present invention, the cutter and clamp being shown in their normal idle positions. Fig. 2, is a vertical cross section in the plane indicated by the line 2—2 in Fig. 1. Fig. 3, is a vertical cross section in the plane indicated by the line 3—3 in Fig. 1. Fig. 4, is a plan view partly in section similar to Fig. 1, excepting that the illustrated parts are shown in the position which they occupy when the cutter and clamp are at work. Fig. 5, is a vertical cross section in the plane indicated by the line 5—5 in Fig. 4. Fig. 6, 50 in a vertical section in the plane indicated by the line 6—6 in Fig. 5.

A, is the lay and B, is the shuttle box at the replenishing side of the loom. Normally

the lay and this shuttle box swing in unison. In case the running weft approaches exhaustion the replenishing instrumentalities are set into action; and, as explained in the aforesaid patent, the shuttle box B, stops as the lay is moving forward while the lay continues its forward movement. In Fig. 1, 55 of the accompanying drawings, the lay and the shuttle box B, are shown in their normal relative positions. Fig. 4, shows the shuttle box B, in its stopped position while the lay is shown at "front center," that is to 60 say, at its most forward position. As shown in Fig. 4, the lay has moved forward relatively to the now stationary shuttle box B. In said patent, there is a complete explanation of the mechanism for producing this 65 particular result. It suffices at the present time to know that the shuttle box B, at the replenishing side of the loom is stopped when a change of weft is called while the lay continues to move forwardly. This relation between the lay and the shuttle box B, is utilized in accordance with the present invention for the purpose of actuating the spent weft cutter and the spent weft clamp. 70

The spent weft cutter comprises a cutting 80 blade C, which, as shown in Fig. 1, is integral with a hub D, secured to the inner end of a rock shaft E, by a set screw F. This rock shaft E, is journaled in bearings G and H, secured to the rear of the lay. The spent 85 weft cutter is located between the warp K, and the mouth of the shuttle box B. At its outer end the rock shaft has a pinion L, fast thereon. Coöperating with this pinion 90 is an internal rack M, carried by a lever N, which is pivoted at O, to a rearward extension P, of the bearing H. The lower end of this lever has a cam slot Q, in which enters at all times a stud R, which is fast on the shuttle box. When the shuttle box B, and 95 the lay are moving in unison, the lever N, occupies the upright position shown in Fig. 3, and the cutter C, occupies its normal idle position back of the reed, as shown in Fig. 1. In the event, however, that a change of weft 100 is called by the approaching exhaustion of the weft in the shuttle, the shuttle box B, stops while the lay continues its forward movement as explained in patent. The result is that the stud R, remains still while 105 the pivot O, of the lever N, moves forwardly

to the position shown in Fig. 4, and hence the lever N, is swung on its pivot and the rack M, swings downwardly thus rocking the shaft E, through the pinion L. Hence 5 the spent weft cutter C, swings forwardly and downwardly to the position shown in Figs. 4 and 5.

At the close of its downward swing the cutter enters a recess S, in the upper face of 10 the lay alongside a stationary shear blade T, located within the recess. Before the cutter C, swings downwardly the shuttle is in the shuttle box B (as indicated at U, in Fig. 4) so that there is a strand of weft V, 15 extending from the fell of the cloth and overlying the stationary shear blade T, in the path of the cutter. Hence, when the cutter descends it encounters the strand V, of the weft and cuts it. The stationary 20 shear blade T, has an upward and rearward extension W, at the rear and back of the reed which serves as a guide for the cutter C, during its downward swing. A spring I, surrounding the rock shaft E, and bearing 25 against a collar a, on said shaft maintains the cutter C, at all times in contact with the blade T, thus insuring the cutting action.

It is important that the strand of weft should be clamped close to the stationary 30 shear blade T, at the time that it is cut and for this purpose a clamp X, is employed. This clamp X, is loosely hung on the rock shaft E. It has a broad laterally extending clamping foot Y, against which bears a 35 spring Z, the other end of which is fastened to the hub D, of the cutter. The clamp X, has at its rear a lateral projection b, which extends back of the cutter C, as shown in Fig. 4. Normally, when the cutter C, 40 occupies its idle position the spring Z, maintains the projection b, of the clamp X, against the rear of the cutter C, as shown in Fig. 2, so that the foot Y, of the clamp is forward of the cutting edge of the cutter. 45 This relation between the cutter and clamp is maintained by the spring Z, during the downward and forward swing of the cutter until the position is reached which is shown in dotted lines in Fig. 2, with the foot of 50 the clamp bearing upon the face of the lay alongside of the recess S, and clamping the strand V, of weft. Thereafter, during the further descent of the cutter C, to the position shown in Fig. 5, the clamp maintains 55 its clamping position, the yielding of the spring Z, between the clamp and cutter permitting this independent movement of the cutter.

When the lay again retreats the shuttle 60 box B, remains stationary until the two are in alinement, when they resume their unison movement as set forth in said patent. During the first part of the retreat of the lay and until it reaches alinement with the shuttle box, the lever N, is restored to the normal

position shown in Fig. 3, by the stud R, and the rock shaft E, is rocked so as to restore the cutter C, and the clamp X, to their normal idle positions, shown in Figs. 1, 2 and 3.

I claim—

1. An automatic weft replenishing loom wherein the shuttle box at the replenishing side of the loom is brought to a standstill before the lay reaches its extreme forward position preparatory to weft replenishment 70 having, in combination, a lay with a recess in its top between the warp and the shuttle box at the replenishing side of the loom; a reed on the lay; a stationary shear blade located in said recess; a rock shaft mounted 80 on the back of the lay having a pinion on its outer end and a cutter on its inner end; a spring acting on said rock shaft to maintain said cutter in contact with the stationary shear blade during the cutting operation; a 85 weft clamp mounted to turn on said rock shaft and yieldingly connected with the cutter so that said cutter may be moved farther than the clamp, said clamp being adapted to clamp a strand of weft against the lay 90 close to the recess therein; a lever pivotally mounted on the lay and having an internal rack engaging said pinion and a cam slot; and a stud on the shuttle box entering said cam slot, whereby said cutter and clamp are 95 normally maintained idle back of the reed but, when the shuttle box stops, the cutter swings into the slot in the lay and the weft clamp clamps the strand of weft to be cut.

2. An automatic weft replenishing loom 100 wherein the shuttle box at the replenishing side of the loom is brought to a standstill before the lay reaches its extreme forward position preparatory to weft replenishment having, in combination, a lay having a recess in its top between the warp and the shuttle box at the replenishing side of the loom; a stationary shear blade located in 105 said recess; a rock shaft mounted on the back of the lay having a pinion on its outer end and a cutter on its inner end; a spring acting to maintain said cutter in contact with the stationary shear blade during the cutting operation; a weft clamp mounted to turn on 110 said rock shaft and yieldingly connected with the cutter so that said cutter may be moved farther than the clamp, said clamp being adapted to clamp a strand of weft against the lay close to the recess therein; a lever pivotally mounted on the lay and having an internal rack engaging said pinion and a cam slot; and a stud on the shuttle box 115 entering said cam slot, whereby said cutter and clamp are normally maintained idle but when the shuttle box stops, the forward movement of the lay through action of said stud on said lever causes said pinion to rotate thereby swinging the cutter forwardly and downwardly into the slot in the lay 120 and causing the weft clamp to move for- 125 130

wardly and downwardly until it clamps the strand of weft extending from the fell of the cloth to the shuttle against the lay.

3. An automatic weft replenishing loom 5 wherein the shuttle box at the replenishing side of the loom is brought to a standstill before the lay reaches its extreme forward position preparatory to weft replenishment having, in combination, a lay having a recess 10 in its top between the warp and the shuttle box at the replenishing side of the loom; a stationary shear blade located in said recess; a rock shaft mounted on the back of the lay having a pinion on its outer end and 15 a cutter on its inner end; a spring acting to maintain said cutter in contact with the stationary shear blade during the cutting operation; a lever pivotally mounted on the lay and having an internal rack engaging 20 said pinion and a cam slot; and a stud on the shuttle box entering said cam slot, whereby said cutter is normally maintained idle but when the shuttle box stops, the forward movement of the lay through action of 25 said stud on said lever causes said pinion to rotate thereby swinging the cutter forwardly and downwardly into the slot in the lay.

4. An automatic weft replenishing loom 30 wherein the shuttle box at the replenishing side of the loom is brought to a standstill before the lay reaches its extreme forward position preparatory to weft replenishment having, in combination, a lay; a rock shaft 35 mounted on the lay having a pinion and a cutter; a lever pivotally mounted on the lay and having an internal rack engaging said pinion and a cam slot; and a stud on the shuttle box entering said cam slot, whereby 40 said cutter is normally maintained idle but when the shuttle box stops, the forward movement of the lay through action of said stud on said lever causes said pinion to rotate thereby swinging the cutter.

45 5. An automatic weft replenishing loom wherein the shuttle box at the replenishing side of the loom is brought to a standstill before the lay reaches its extreme forward position preparatory to weft replenishment 50 having, in combination, a lay; a movable cutter on the lay; and actuating means for

the cutter connected with the shuttle box so that when the shuttle box stops and the forward movement of the lay continues the cutter moves to cut the strand of weft extending from the fell of the cloth to the shuttle. 55

6. An automatic weft replenishing loom 60 wherein the shuttle box at the replenishing side of the loom is brought to a standstill before the lay reaches its extreme forward position preparatory to weft replenishment having, in combination, a lay having a recess 65 in its top between the warp and the shuttle box at the replenishing side of the loom; a stationary shear blade located in said recess; a movable cutter on the lay; a spring acting to maintain said cutter in contact with the stationary shear blade during the cutting operation; and actuating means for the cutter 70 connected with the shuttle box so that when the shuttle box stops and the forward movement of the lay continues the cutter moves into the slot in the lay and cuts the strand of weft extending from the fell of 75 the cloth to the shuttle.

7. An automatic weft replenishing loom 80 wherein the shuttle box at the replenishing side of the loom is brought to a standstill before the lay reaches its extreme forward position preparatory to weft replenishment having, in combination, a lay having a recess 85 in its top between the warp and the shuttle box at the replenishing side of the loom; a movable cutter on the lay; a weft clamp 90 mounted on the lay to move with the cutter and yieldingly connected with the cutter so that said cutter may be moved farther than the clamp, said clamp being adapted to clamp a strand of weft against the lay close to the recess therein; and actuating means for the cutter connected with the shuttle box so that when the shuttle box stops and the forward movement of the lay continues the cutter moves into the slot in the lay and 95 causes the weft clamp to move until it clamps the strand of weft extending from the fell of the cloth to the shuttle against the lay.

In witness whereof, I have hereunto signed 100 my name.

EUGENE H. BALLOU.
